(57) **CLAIM**

The ornamental design for a pet travel bottle, as shown and described.

DESCRIPTION

FIG. 1 is a top front perspective view from the front of a pet travel bottle showing our new design;

FIG. 2 is a bottom, rear view thereof;

FIG. 3 is a front elevation view thereof;

FIG. 4 is a rear elevation view thereof;

FIG. 5 is a left side elevation view thereof, the right side elevation being a mirror image thereof;

FIG. 6 is a top view thereof;

FIG. 7 is a bottom view thereof;

FIG. 8 is a top, front perspective view of the drinking sleeve, shown separately for completeness of the illustration;

FIG. 9 is a bottom, rear perspective view thereof;

FIG. 10 is a front elevation view thereof;

FIG. 11 is a rear elevation view thereof;

FIG. 12 is a left side elevation view thereof, the right side elevation being a mirror image thereof;

FIG. 13 is a top view thereof;

FIG. 14 is a bottom view thereof;

FIG. 15 is a top, front perspective view of the bottle, shown separately for completeness of the illustration;

FIG. 16 is a bottom perspective view thereof;

FIG. 17 is a front elevation view thereof;

FIG. 18 is a rear elevation view thereof;

FIG. 19 is a left side elevation view thereof;

FIG. 20 is a right side elevation view thereof;

FIG. 21 is a top view thereof; and,

FIG. 22 is a bottom view thereof.

(Continued)

The dotted lines are for illustrative purposes only and form no part of the claimed design.
